UNITED STATES PATENT OFFICE

123,463

DESIGN FOR A SPEEDBOAT OR THE LIKE

Henry Silverstein, Brooklyn, N. Y.

Application November 25, 1939, Serial No. 88,475

Term of patent 14 years

To all whom it may concern:

Be it known that I, Henry Silverstein, a citizen of the United States, residing at No. 1596 St. Marks Avenue, Brooklyn, in the county of Kings and State of New York, have invented a new, original, and ornamental Design for a Speedboat or the like, of which the following is a specification, reference being had to the accompanying drawing, forming part thereof.

In the drawing:

Fig. 1 is a top plan view of a speedboat showing my new design;

Fig. 2 is a side elevational view;

Fig. 3 is a front elevational view; and

Fig. 4 is a rear elevational view thereof.

I claim:

The ornamental design for a speedboat or the like, as shown.

HENRY SILVERSTEIN.
